UNITED STATES PATENT OFFICE.

PHILO M. BARNES, OF LOCKPORT, NEW YORK.

BUGGY-BOOT.

SPECIFICATION forming part of Letters Patent No. 391,009, dated October 16, 1888.

Application filed June 12, 1888. Serial No. 276,877. (No model.)

To all whom it may concern:

Be it known that I, PHILO M. BARNES, a citizen of the United States, residing in Lockport, in the county of Niagara and State of 5 New York, have invented certain new and useful Improvements in Buggy-Boots, of which the following is a specification.

My invention relates to certain improvements in boots for buggies, and will be fully 10 and clearly hereinafter described and claimed, reference being had to the accompanying drawings, in which—

Figure 1 is a perspective view of a portion of a light wagon showing my invention connected thereto. Fig. 2 is an inside view of a 15 buggy-boot complete. Fig. 3 is also an inside or under side view of a buggy-boot, showing the supporting-frame in place before the last covering is put on. Fig. 4 is a perspective 20 view of the supporting-frame, and Fig. 5 is an enlarged sectional elevation through line *a b*, Fig. 2.

The outside or shell 1 and its inclined portion 2 is made of wood pulp or Manila fiber. 25 The rear portion, 1, is provided with a downwardly-projecting edge or rim, 3, adapted to fit the back part of a wagon or buggy, and the inclined portion 2 is a thin flat piece adapted to lie on and be secured to the inclined edges 30 of a wagon or buggy. The wood pulp or Manila fiber is rendered sufficiently soft to be worked by being soaked in water, and is then pressed over a metallic frame, 4, which brings it into the proper shape and allows the edges 35 3 to be formed over into shape, and is then held in shape by any well-known means until dry. During the process of drying it shrinks to a certain extent; consequently the frame 4 is removed and a smaller one, 5, (see Fig. 3,) 40 adapted to fit, is put in its place. When it is formed and thoroughly dry, it is cleaned and smoothed off and then soaked in boiled linseed-oil, which renders it water-proof and brings it into a condition that it can neither 45 shrink nor warp. It is now coated with enamelled-leather varnish and put into an oven and

baked until sufficiently hard and dry. It is then lined on the inside with a heavy canvas, 6, (see Fig. 5,) to make it stiffer and stronger, the canvas being secured thereto by glue or 50 other suitable cement. A covering of cloth, 7, or other similar material for a finish, is now put on and secured by glue or cement.

The boot when complete is provided with two long straps, 8, and two short ones, 9, (see 55 Figs. 2 and 5,) secured thereto in any well-known way—for instance, by the rivets 10. It is held in place by pins 12 or screws to the under side of the seat 13, substantially as shown in Fig. 1.

By this construction a very strong and durable water-proof buggy-boot is formed and the outer portion is entirely in one piece without seams.

I claim as my invention—

1. A buggy-boot consisting of an outer portion or body, 1 2, of water-proof fibrous material formed into shape over a metal frame and strengthened by an inside lining of heavy canvas provided with a covering over the canvas, 70 substantially as described.

2. A buggy-boot consisting of the body water-proof portion 1 2, formed without seams and secured by a metal frame, and a lining of canvas having a covering of cloth and provided 75 with straps 8 9, substantially as described.

3. A buggy boot consisting of the body portion 1 2, formed without seams, of wood pulp, and provided with a metallic strengthening-frame, and a lining of heavy canvas on the inside having a covering of cloth, and having 80 straps 8 9, substantially as and for the purposes described.

4. In a buggy-boot, the combination of the body 1, 2, and 3, strengthening-frame 5, canvas lining 6, covering of cloth 7, and straps 8 9, substantially as described.

PHILO M. BARNES.
